[57] CLAIM

The ornamental design for a push lock, as shown and described.

DESCRIPTION

FIG. 1 is a top, front perspective view of a handle showing my new design;

FIG. 2 is a front elevation view thereof;

FIG. 3 is a top plan view thereof;

FIG. 4 is a right side elevation view thereof, the left side being a mirror image of the right side;

FIG. 5 is a bottom plan view thereof;

FIG. 6 is a rear elevation view thereof; and,

FIG. 7 is a front view of a second alternate embodiment thereof, the top, back and side views being the same as those shown in FIGS. 3-6.

The broken lines are shown for illustrative purposes only and form no part of the claimed design.
